CLAIM

The ornamental design for a spray gun, as shown and described.

DESCRIPTION

FIG. 1 is a perspective view of a spray gun showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of encircled portion "9" in FIG. 1;

FIG. 10 is an enlarged view of encircled portion "10" in FIG. 1; and,

FIG. 11 is an enlarged view of encircled portion "11" in FIG. 1.

Broken lines in FIGS. 1-8 illustrate portions of the spray gun that form no part of the claimed design.

1 Claim, 11 Drawing Sheets
